ELECTRIC ROASTER

Guy H. Allgeyer, Toledo, Ohio, assignor, by mesne assignments, to Tropic-Aire, Inc., Chicago, Ill., a corporation

Application February 8, 1950, Serial No. 7,814

Term of patent 14 years

(Cl. D81—10)

To all whom it may concern:

Be it known that I, Guy H. Allgeyer, a citizen of the United States, residing at Toledo, State of Ohio, have invented a new, original, and ornamental Design for an Electric Roaster, of which the following is a specification, reference being had to the accompanying drawing, forming a part hereof.

The dominant feature of my design resides in the escutcheon plate element of the electric roaster, shown in full lines.

I claim:

The ornamental design for an electric roaster, as shown and described.

GUY H. ALLGEYER.
